UNITED STATES PATENT OFFICE

2,442,527

METHOD AND APPARATUS FOR MAKING
GROOVED CAPSLawrence G. Zesbaugh, Minneapolis, Minn., as
signor to John G. O'Neil, Faribault, Minn.

Application April 21, 1943, Serial No. 483,921

11 Claims. (Cl. 93—36)

1

This invention relates to a method and apparatus for forming a ring or cap, and particularly for forming a grooved ring or cap. Caps with grooves or threads formed therein on the inner cylindrical wall thereof are now commonly used as tops or closures for many kinds of containers.

It is an object of this invention to provide a simple and efficient method and apparatus for forming a grooved or threaded cap of material adapted to be pressed into shape, said cap being so formed that it can readily be removed from the apparatus.

It is a further object of this invention to provide a method whereby a groove and rib can be formed on the inner wall of a cap, said groove or rib and groove being formed in successive steps, part of the same being formed in one step and part in another step.

It is still another object of the invention to provide a method for forming a groove or groove and rib on the inner wall of a cap which consists of forming circumferentially spaced portions of said groove in one operation and subsequently forming the alternate portions of said groove in another operation.

It is also an object of this invention to provide a method and apparatus for forming a grooved cap or ring comprising an inner die having a projecting rib formed thereon, an outer die adapted to move over a cap placed on said inner die and having portions closely fitting said cap so that said cap is pressed against said inner die at said portions, said outer die also having portions of larger dimension which do not engage said cap tightly and into which portions of said cap may extend, a second outer die having circumferentially spaced portions adapted to closely fit said cap to press portions thereof against said inner die and also having circumferentially spaced portions of larger dimension, said dies being so arranged that the said larger portions of said outer dies are alternately arranged whereby said cap will be grooved for substantially its whole extent but will not be made to firmly adhere to said inner die.

It is further an object of the invention to provide an apparatus for forming a cap comprising an inner die having a projecting rib on its periphery, an outer die adapted to move over a cap placed over said inner die to compress said cap longitudinally and form a groove therein by means of said inner die, said outer die also having a portion engaging the top of said cap and adapted to form a circumferential groove therein.

It is also an object of the invention to provide

2

an apparatus for forming a grooved cap comprising an inner die having means thereon to form a groove in said cap, said inner die having a rigid portion for supporting the edge of said cap, an outer die movable over a cap disposed on said inner die and adapted to compress said cap, said outer die being yieldingly mounted.

It is further an object of the invention to provide such an apparatus as set forth in the preceding paragraph, said outer die having a portion for engaging to top of said cap which is unyielding and said inner die having a portion engaging the inside of said top portion of the cap which is yieldingly mounted.

These and other objects and advantages of the invention will be fully set forth in the following description made in connection with the accompanying drawings in which like reference characters refer to similar parts throughout the several views and in which:

Fig. 1 is a view partly in side elevation and partly in central vertical section of the dies and plungers used in forming the cap;

Fig. 2 is a central vertical section of one of the sets of dies in cap forming position;

Fig. 3 is a partial vertical section on an enlarged scale of the cap forming portion of the dies;

Fig. 4 is a horizontal section taken on line 30 4—4 of Fig. 2 as indicated by the arrows;

Fig. 5 is a horizontal section taken on line 5—5 of Fig. 1 as indicated by the arrows;

Fig. 6 is a horizontal section similar to Fig. 5 taken through the cap rim;

Fig. 7 is a somewhat diagrammatic plan view of the die-carrying turret and cooperating plunger, a portion being shown in horizontal section;

Fig. 8 is a partial vertical section through the 40 finished cap; and

Fig. 9 is a central vertical section through the cap before being placed in the dies.

Referring to the drawings, a machine is shown which comprises lower die assemblies 15 and 45 upper die assemblies 16, 17 and 18. While these may be variously arranged, one desirable arrangement is that illustrated in Fig. 7 where the lower dies 15 will be carried on a revoluble turret 19. While this turret could revolve in either 50 direction, in the embodiment of the invention illustrated it is rotated in the direction indicated by the arrow in Fig. 7. The method and apparatus of the invention are directed to forming grooves or threads on a ring or cap and while 55 various forms of blanks might be used in the

embodiment of the invention illustrated a blank or partly finished cap 20 shown in Fig. 9 is used. This cap comprises a ring 20a of some compressible dense material such as cardboard, fiber, etc. A cup-like portion 20b extends along the inner wall of ring 20 and across the top thereof and this can be made of lighter sheet material of fiber, paper, etc. Preferably a sealing disk 20c is used which is placed underneath the top 20b and is somewhat softer sheet material such as paper or fiber and is adapted to engage the top of the container. The grooved cap could also be formed of various metals.

The lower dies 15 are of similar construction and comprise an outer cylindrical portion 15a having a flange secured to a base or the turret 19 by circumferentially spaced screws 22. A member 15b fits inside of member 15a, being vertically slidable relatively thereto, the same having a lower outwardly extending flange 15c adapted to engage a shoulder adjacent the bottom of member 15a to limit its upward movement. Member 15b at its top portion is of reduced diameter and has secured thereto in any suitable manner as by the threads shown, a ring 15d of hard metal. This ring as shown, has formed on its periphery, ribs 15e. While ribs 15e could be variously formed, in the embodiment of the invention illustrated they are arranged as helices or threads. Member 15b has a top disk-like portion with a central aperture 15f and a member 23 having a tapered or frustoconical top portion extends slightly into opening 15f. A screw 24 is threaded into the plug or member 23 and has a head disposed below the same. Plug 23 has a depending portion 23a of reduced diameter loosely fitting into the top of a compression coiled spring 25 which rests on the base or turret 19. Plug 23 has another portion 23b extending downwardly into spring 25 and the head of bolt 24 extends downwardly into spring 25. Member 15a has a hollow groove or channel 15g at its inner edge adjacent member 15b.

Cooperating with the dies 15 are the upper dies 16, 17 and 18 and in the embodiment of the invention illustrated these are shown as carried in a plunger head 27 carried on a plunger 28 which will be reciprocated by some suitable operating mechanism. Die assembly 16 comprises a member 16a of general cylindrical form having an opening 16b which is of a diameter sufficient to move over and surround the blank 20 carried on the lower die assembly 15. Member 16 is slidable on an inner member 16c which is seated rigidly in member 27 and secured therein by the headed screw 28. Compression coiled springs 29 have one end seated in recesses in member 27 and their other ends seated in recesses in member 16a. Member 16a has an inwardly extending flange 16d engaging the shoulder on member 16c, said flange limiting the downward movement of member 16a. Member 16c is provided adjacent its edge with a V-shaped rib 16e and also has a sharp ridge 16f at its edge which extends downwardly. The die assembly 17 is similar in construction to die member 16 in having member 17a and member 17c as well as the compression coiled springs 29. Member 17c is also held in place by one of the screws 28. Member 17a has an opening therein which is also of sufficient size to move over the cap 20 disposed on the lower die and member 17a has a flange 17d engaging the shoulder on member 17c to limit the downward movement of member 17a. Member 18 has a portion 18a similar to members 16a and 17a and said die assembly

also has an inner member 18c similar to members 16c and 17c. Compression coiled springs 29 hold member 18a downwardly and its downward movement is limited by the flange 18d engaging a shoulder on member 18c. Members 17c and 18c have the ridges 17e and 18e respectively, similar to the ribs or ridges 16e and also have the outer ribs 17f and 18f similar to the ridges 16f. Member 17a differs from member 16a however, in that its opening 17b instead of being perfectly cylindrical has enlarged portions 17g and while the number of these portions might vary, in the embodiment of the invention illustrated they are shown as four in number and equally spaced about member 17a. Member 18a also has enlarged portions 18g about its opening 18b which are similar to the portions 17g and these are equally and circumferentially spaced and shown as four in number. The die assemblies 17 and 18 will be so disposed in member 27 that the portions 18g will alternate with the openings 17g relative to the lower die or in other words, the portions 18g will be disposed between the portions 17g in relative location. The lower portion of the openings 16b, 17b, and 18b are slightly outwardly beveled at their lower edge as shown at 16h in Fig. 1. This bevel of course will be present in members 17a and 18a between the enlargements 17g and 18g. Ribs 17f and 18f are omitted at the enlarged portions 17g and 18g as shown in Fig. 5.

In performing the method of the invention, in the embodiment of the apparatus illustrated, the blanks or caps 20 which have been previously assembled will be placed on the lower die assemblies 15 by one or more operators stationed about turret 19. This turret will be intermittently rotated distances equal to the circumferential distance between the die assemblies 15. The cap placed on the lower die 15 will first come under the member 16a or the die assembly 16. As the plunger 28 descends member 16a will surround the cap 20 and will move downward until its lower surface engages the top surface of member 16a. Its movement will thus be arrested and further downward movement of member 27 will compress the springs 29. Member 16c moves downwardly and the cap 20 is compressed and it will be moved somewhat lightly against the ribs 16e. The pressure of the cap against ribs 16e will not however, be sufficient to form completed grooves in the inner wall of the cap. The ribs 16e form a groove in the top of the cap just inwardly of ring 20 as shown in Fig. 1 and the rib 16f will form a slight bevel at the outer corner of the cap as shown in Figs. 1 and 8. The plunger 27 will now be raised and the turret will be rotated another step, bringing the cap on the lower die assembly 15 beneath die assembly 17. As the die assembly 17 descends member 17a will surround the cap and member 16b will be depressed as before against spring 25 so that the lower edge of the ring part of the cap will seat in the groove 15g. The member 17a will surround the cap and at the portions between portion 17g the side of the cap will be forced very strongly against the member 16d and its ribs 16e. The grooves and ribs formed in the cap will thus be completely formed at these portions between portions 17g. The cap can expand slightly into the enlarged portions 17g and the cap will not be caused to adhere very tightly to the member 16d. Plunger 27 is again raised and the cap now rotates with the turret and is brought beneath the die assembly 18. As this descends with member 27 the cap is again compressed between members 18a and

15d and the portions thereof which occupied the enlarged portions *17g* now are disposed between the portions *18g* and these portions have the wall of the cap forced very firmly and strongly against member *15d* and the ribs *15e* so that the grooves and ribs formed on the cap are now formed completely about the same. It will thus be seen that part of the cap is finished by die assembly *17* as to the grooves and ribs and the remainder is finished by the die assembly *18*. The openings *17b* and *18b* may be slightly smaller than the opening *16b*. When the portions of members *18a* between enlarged portions *18g* engage the cap and force it against the ribs *15e* other portions of the cap can expand slightly into the openings *18g* and will thus not be tightly engaged. As a result, the cap will not be caused to adhere tightly to the member *15d*. It has been found in practice that if the threads are formed completely around the cap in one operation the cap adheres so tightly to the die that difficulty is experienced in removing it. With the present method and apparatus the threads are formed in several operations and the cap is not tightly fastened to the die and can be easily removed. The slight bevel *16h* enables the die to move easily over the cap *20* on the lower die. This bevel obviates having the dies in extremely accurate axial alignment.

From the above description it will be seen that I have provided a very efficient method and apparatus for forming a grooved or threaded cap or ring. The grooves or threads are perfectly formed in the cap and the cap can very readily be removed from the die assembly *15*. In practice the caps will be removed by operators stationed about the turret *19*. It will be noted that there are openings or passages *28a* and *24a* through the screws *28* and *24* respectively and passages *23a* in the members *23*. Any air that might be trapped in the dies can thus readily escape. It will be noted that the cap is held on the inner die and is surrounded by the outer die before any compression of the same takes place. This obviates moving an inner die into an outer die with the cap compressed in such movement. In the present apparatus the compression is done by the portions *16c*, *17c* and *18c* after the cap has been surrounded. A metal die thus does not have to enter another metal member in which it closely fits. This also eliminates the necessity of maintaining an extremely accurate axial alignment of the upper and lower die assemblies. With the apparatus shown, the caps can be made at a very rapid rate. As described, they are successively acted on by the upper die assemblies *16*, *17* and *18* to be formed as desired and are then removed as the lower dies move away from the plunger head *27*. The method and apparatus have been amply demonstrated in actual practice and found to be very successful and efficient.

It will of course, be understood that various changes may be made in the form, details, arrangement and proportions of the apparatus and in the steps and sequence of steps of the method without departing from the scope of applicant's invention, which generally stated, consists in a method and apparatus capable of carrying out the objects above set forth, such as disclosed and defined in the appended claims.

What is claimed is:

1. The method of forming a thread on a cap having a cylindrical flange thereon which consists in forming circumferentially spaced grooves on said flange at circumferentially spaced portions thereof in one pressing operation by com-

pressing said flange longitudinally to force it against a cylindrical die having circumferentially spaced thread-forming means thereon and then in a second operation forming said grooves in the alternate circumferentially spaced portions by again compressing said flange longitudinally to force said latter portions against said die.

2. An apparatus for forming a grooved cap or ring having in combination, an inner die having a continuous periphery with a peripheral rib formed thereon, a rigid outer die adapted to move over a cap placed on said inner die and compress the same longitudinally, said outer die having circumferentially spaced portions for tightly engaging said cap when the same is compressed longitudinally and circumferentially spaced portions of larger transverse dimension remaining free of said cap when the latter is compressed longitudinally, a second rigid outer die adapted to move over said inner die in a

subsequent operation and compress said cap longitudinally and having circumferentially spaced portions for tightly engaging said cap when compressed in said subsequent operation and circumferentially spaced portions of larger transverse dimension remaining free of said cap when the same is compressed in said subsequent operation, said latter portions being arranged circumferentially so as to be disposed between the corresponding portions on said first mentioned outer die whereby in successive operations different portions of said cap will be pressed against said inner die to form a substantially complete groove therein.

3. An apparatus for forming a grooved cap having in combination, an inner die having a continuous substantially cylindrical portion with a circumferentially extending projecting rib thereon, a rigid outer die having a substantially cylindrical portion adapted to move over said inner die and a cap carried thereon, means for compressing said cap longitudinally, said outer die having circumferentially spaced portions of one dimension tightly fitting said cap against which and said rib said cap is forced by said means and circumferentially spaced portions between said portions of a larger transverse dimension remaining free of said cap when the same is compressed, a second outer die adapted

to move over said cap and inner die in a subsequent operation, said latter die having circumferentially spaced portions of one dimension against which and said rib said cap is forced by said means and circumferentially spaced portions of a larger transverse dimension remaining free of said cap when the same is compressed, said outer dies being arranged relatively to said inner die so that said portions of larger dimension are alternately disposed.

4. An apparatus for forming a cap with a grooved or threaded inner wall having in combination, inner and outer dies having thread-forming means on one of the same, means for compressing said cap longitudinally between said dies, said first mentioned means having circumferentially spaced operative portions and inoperative portions between said portions.

5. An apparatus for forming a thread on the flange of a cap having in combination, an inner die adapted to receive said cap and having a continuous periphery about which said flange extends, a rigid outer die adapted to surround said cap and die, means for compressing said flange longitudinally between said dies, said dies having cooperating portions against which said

70

75

flange is pressed by said compression to form a thread thereon; said portions being interrupted at circumferentially spaced parts of one of said dies.

6. An apparatus for forming a thread on the cylindrical flange of a cap having in combination, an inner die having a continuous periphery adapted to be disposed in said flange, a rigid outer die adapted to surround said flange and die, said dies having cooperating portions adapted to press the wall of said flange therebetween to form a groove therein, said portions on said outer die being circumferentially spaced, and a second outer die having similar circumferentially spaced portions adapted to alternate with said spaced portions in said first mentioned outer die in cooperation with said inner die whereby a completed groove is formed in said flange and means for longitudinally compressing said flange between said dies in successive steps to force said flange thereagainst in successive steps.

7. An apparatus for forming a threaded cap having in combination, an inner die having a continuous periphery with a projecting rib thereon, an outer die having a continuous inner wall adapted to surround said inner die and flange, means for compressing said flange longitudinally between said periphery and wall to force the same thereagainst to form a rib and groove therein, said outer die having circumferentially spaced portions of a size to closely engage said cap and having circumferentially spaced portions of larger transverse dimension remaining free of said cap.

8. An apparatus for forming a thread on the cylindrical flange of a cap having in combination, a rigidly mounted lower die having a surface to support the edge of said flange and having a continuous yielding portion with a peripheral wall disposed at the inner side of said flange, a rigid outer die adapted to move over said flange on said periphery of said lower die, said dies comprising thread-forming means, said outer die being mounted for resilient movement, said outer die having a rigidly mounted upper portion adapted to engage the top of said cap to compress said flange longitudinally and force it against said thread-forming means.

9. The structure set forth in claim 8, said last mentioned portion of said upper die having a V-shaped ring on its lower surface for forming a circumferentially extending groove in the top of said cap adjacent the edge thereof, and having a rib adjacent its top for forming a bevel at the outer edge of said cap on the top thereof.

10. An apparatus for forming a thread on the substantially cylindrical flange of a cap having in combination, inner and outer rigid dies adapted to receive said flange therebetween and surround the same, said dies including circumferentially spaced means for pressing part of a thread in said flange, said means being operated in successive steps with said dies in different circumferential relation whereby said flange can be easily removed from said dies and a complete thread is formed therein and means for compressing said flange longitudinally in said successive steps to press it against said dies.

11. The method of forming a thread on the substantially cylindrical flange of a cap which consists in disposing said flange between rigid inner and outer dies, said dies including circumferentially spaced means for pressing part of a thread in said flange, compressing said flange longitudinally to force it against said dies in successive steps with said dies in different circumferential relation whereby a complete thread is formed in said flange.
